UNITED STATES PATENT OFFICE.

GEORGE F. CONNER, OF PORT HURON, MICHIGAN.

DESIGN FOR A LEVEL.

SPECIFICATION forming part of Design No. 32,390, dated March 27, 1900.

Application filed March 1, 1900. Serial No. 7,021. Term of patent 14 years.

To all whom it may concern:

Be it known that I, GEORGE F. CONNER, a citizen of the United States, residing at Port Huron, in the county of St. Clair and State of

Michigan, have invented and produced a new and original Design for Levels, of which the following is a specification, reference being had to the accompanying drawing, forming a part thereof.

10 This invention relates to a new and original design for levels; and it consists in the configuration and shape hereinafter described and shown in the accompanying drawing.

The design is shown in the accompanying drawing in perspective, and consists in a casting having two raised portions B at its outer edge of substantially rectangular formation. The upper faces of the raised portion are formed with oblong openings C, below which 20 are the transparent tubes. Between the arms

of the raised portion in the angle formed thereby is a flat web D, having an opening therein and having a curved outer edge, substantially as shown.

The essential feature of the design is the 25 casting having raised portions at right angles to one another, with the oblong openings and the flat web between the raised portions in the angle, substantially as shown.

Having thus described my invention, what 30 I claim as new, and desire to secure by Letters Patent, is—

The design for a level, substantially as shown and described.

In testimony whereof I have affixed my signature in presence of two witnesses.

GEORGE F. CONNER.

Witnesses:

S. A. WOOD,
H. B. HOYT.
